UNITED STATES PATENT OFFICE.

HERMAN W. MAURER, OF CLEVELAND, OHIO.

FOLDING PARTITION.

Application filed July 9, 1921. Serial No. 483,540.

To all whom it may concern:

Be it known that I, HERMAN W. MAURER, a citizen of the United States, residing at Cleveland, in the county of Cuyahoga and 5 State of Ohio, have invented certain new and useful Improvements in Folding Partitions, of which the following is a specification.

This invention relates to folding partitions for dividing rooms and other similar purposes and more particularly to partitions of flexible material which will permit folding of same.

The main object of the invention is to 15 provide a folding partition which when unfolded may be locked to the floor to hold the partition securely in a stretched position.

Another object of the invention is to provide a folding partition having spaced walls 20 to prevent the penetration of sounds there-thru.

Another object of the invention is to provide a folding partition of inexpensive construction and that is convenient and easy 25 to operate.

With the above and other objects in view as will be readily understood, the invention will be hereinafter fully described as illustrated in the accompanying drawings, and the novel features thereof will be distinctly pointed out in the appended claims.

In the drawings similar characters of reference are used to designate corresponding 35 parts.

Figure 1 illustrates a pair of sections of a folding partition constructed in accordance with my invention, one of the sections being in its closed position and the other being in 40 the open position.

Fig. 2 is a similar view to Fig. 1, the near side of each section being omitted to better show the construction.

Fig. 3 is an enlarged cross sectional view 45 taken on line 3—3 of Fig. 2,

Fig. 4 is a similar view taken on line 4—4 of Fig. 2,

Fig. 5 is a sectional elevation, on an enlarged scale, taken on line 5—5 of Fig. 2,

50 Fig. 6 is a similar view taken on line 6—6 of Fig. 2,

Fig. 7 is an enlarged sectional view taken 55 on line 5—5 of Fig. 2, illustrating the mechanism for supporting the upper edges of the sides of the partition,

Fig. 8 is a similar view taken on line 6—6 of Fig. 2, illustrating the means for forcing the upper inner end of the partition inwardly and for holding the corners thereof in vertical alinement. 60

Fig. 9 illustrates a front view of the means for locking the sections to the floor,

Fig. 10 is an end view of same, and

Fig. 11 is a plan view illustrating the arrangement of the pulley wheels fixed to the 65 board to which is hinged the floor board.

Referring to the drawings, 1 represents the floor of a room, 2 and 3 opposite side walls, and 4 the ceiling. In dividing a room by means of the partition of this invention, it 70 is preferable to employ two similar sections as 5 and 6, which extend from the side walls 2 and 3 and meet in the center of the room. Each section consists of a vertical board 7 which is fixed to the respective side walls 2 75 and 3, and from this board extends a short piece of board 8 which is fastened to the floor. To the board 8 is hinged at 9 a floor board 10, which extends almost to the center of the room and is adapted to swing upwardly. 80 Sides 11 and 12 of canvas or other suitable flexible material are fixed to the edges of the vertical board 7, the short piece of board 8 and the floor board 10, by tacks 13, and the inner edges of said sides are connected 85 by a vertical strip of canvas 14, which passes under said floor board and is secured thereto and to the lower end of said sides. The upper edges of the sides 11 and 12 are supported by means of hooks 15 passing thru 90 eyelets 16, which are fastened to said sides. Each of the hooks 15 depends from a cross-bar 17, which is supported by a pair of roller-wheels as 18 at its ends, and said pair of roller-wheels are adapted to travel with- 95

in the respective slotted tracks 19 and 20, which are fixed by screws as 21 to the ceiling 4 above the sides 11 and 12. Any suitable device may be employed for holding the board 10 and therefore the lower edge 100 of the partition to the floor, as for instance a spring catch 22 fixed to the edge of said board, which catch is adapted to engage a keeper member 23 projecting from the floor.

For drawing the partition into its folded up position, the floor board 10 is lifted upon its hinge 9 and the upper part of the partition moved inwardly by means of the following described mechanism. A cord 24 having one of its ends attached at 105 25 to 110

the floor board 10 passes thru rings 26 attached to the inside of the side 12 and arranged in the arc of a circle, then over a pulley 27 supported by the vertical board 5 7 and under a pulley-wheel 28 fixed to the short piece of board 8. The cord 24 then passes over a sheave of a floating double pulley-block 29, and under a pulley-wheel 30 also fixed to the floor board 8, then upwardly and over a pulley 31 supported by the vertical board 7, and then thru rings 32 attached to the inside of said side 12 and also arranged in the form of the arc of a circle, and its free end is fastened at 10 15 33 to the floor board 10. A cord 34 similarly arranged is connected with the side 11 as is the cord 24 with the side 12, has its ends fastened to the floor board 10 at points 35 and 36 opposite 25 and 33, and passes over pulleys 20 37 and 38 opposite the pulleys 27 and 31, and under pulley-wheels 39 and 40 opposite the pulley-wheels 28 and 30, and its looped part therebetween over the other sheave of the floating double pulley-block 29. A pull- 25 30 rope 41 is attached to the eye of the floating double pulley-block 29, and passes upwardly thru an opening in the ceiling, then over a pulley 42 and downwardly over a pulley 43 and at its free end is a handle 44, a suitable means as 45 may be employed to hold the free end of the pull-rope to retain the partition in its folded up position.

In order to cause the upper inner ends of the sections of the partition to be forced 35 to the center of the room when said sections are being closed and to hold the edges of said inner ends of the sections for their entire height in close contact when closed, the following described mechanism is employed for each section. A belt 46 is attached at its lower end 47 to the inner end of the floor board 10 and extending upwardly passes over a flanged roller 48, which is rotatably mounted upon a shaft 49 supported at each end from pairs of roller-wheels as 50, similar to the roller-wheels 18, and like them also adapted to travel in the before mentioned slotted tracks 19 and 20. The upper end of the belt 46 50 55 is attached to the center of the ceiling 4 at 51. Ropes 52 and 53 are adapted to hold the corners of the inner end of each section of the partition in rigid alinement when the sections are closed, and for this purpose are attached to the shaft 49 at 54 and 55, and their lower ends to suitable coiled springs 56 and 57, which are connected to the floor board 10 at 58 and 59. The belt 46 forces the roller 48 to its original position upon the pushing downwardly of the floor board 10 to close the section of the partition, the coiled springs 56 and 57 prevent said floor board from falling suddenly to the floor and thereby making a noise, 60 65 and the ropes 52 and 53 being forced into

the inner corners of the section holding same in vertical alinement.

When the sections 5 and 6 of the partition are closed and the catches 22 engage the keeper member 23, each section is held in a stretched position, and the inner edges thereof are also held in vertical alinement and in close contact with each other. As there is an air space between the sides 11 and 12 of the sections, there is little chance for sound penetrating therethru. To pull back or fold up the sections of the partition, it is only necessary to release the catch 22 and pull downwardly upon the handle 44 of the pull ropes 41; and by connecting said handles to the locking means 45, the sections will be held in their open positions. The sections of the partition are readily closed by disconnecting the handles 44 from 45, whereupon the weight of the floor board 10 and lower portions of the sections will fall, thereby causing the belt 46 to force the roller 48 towards the center of the room. The floor boards 10 are then pushed downwardly so that they may be locked to the floor by means of the catches 22, and this causes the ropes 52 and 53 to be forced into the inner corners of the sections thereby holding the same in a vertical position and in close contact.

It will be understood that the details of construction of this partition may be changed from those illustrated and described and still accomplish the desired results without departing from the scope of 100 the claims.

Having fully described my invention what I claim is:

1. In a folding partition, the combination of a pair of sides of flexible material, a support, the sides being arranged in spaced relation and having their outer edges attached to said support, a strip of flexible material connecting the inner edges of said sides, means for supporting the upper edges of said sides, a board, the board being arranged between the lower edges of said sides, the lower edges of said sides being attached to said board, the board being hinged at its outer end to a fixed support and means for swinging said board upwardly to fold the partition, substantially as described.

2. In a folding partition, the combination of a pair of sides of flexible material, a support, the sides being arranged in spaced relation and having their outer edges attached to said support, a strip of flexible material connecting the inner edges of said sides, means for supporting the upper edges of said sides to allow the inner edge thereof to move longitudinally, a board, the board being arranged between the lower edges of said sides, the lower edges of said sides being attached to said board, the board being hinged at its outer end to a fixed support and means ar-

ranged between said sides whereby said board may be swung upwardly to fold the partition, substantially as described.

3. In a folding partition, the combination 5 of a pair of sides of flexible material, a support, the sides being arranged in spaced relation and having their outer edges attached to said support, a strip of flexible material connecting the inner edges of said sides, 10 means for supporting the upper edges of said sides to allow the inner edge thereof to move longitudinally, a board, the board being arranged between the lower edges of said sides, the lower edges of said sides being 15 attached to said board, the board being hinged at its outer end to a fixed support, a pair of cords, pulleys, the cords being attached to said board and passing over said pulleys, pairs of pulley-wheels, a second pair 20 of pulleys, the free ends of said cords passing under said pairs of pulley-wheels and over said second pair of pulleys and being attached to said board, and means whereby said cords may be pulled upwardly between 25 said pairs of pulley-wheels for swinging said board upwardly to fold the partition, substantially as described.

4. In a folding partition, the combination 30 of a pair of sides of flexible material, a support, the sides being arranged in spaced relation and having their outer edges attached to said support, a strip of flexible material connecting the inner edges of said sides, means for supporting the upper edges of 35 said sides to allow the inner edge thereof to move longitudinally, a board, the board being arranged between the lower edges of said sides, the lower edges of said sides being attached to said board, the board being 40 hinged at its outer end to a fixed support, a pair of cords, pulleys, the cords being attached to said board and passing over said pulleys, pairs of pulley-wheels, a second pair 45 of pulleys, the free ends of said cords passing under said pairs of pulley-wheels and over said second pair of pulleys and being attached to said board, a double pulley-block, portions of said cords between said pairs of pulley-wheels passing thru the double 50 pulley-block, and a pull-rope attached to said double pulley-block whereby said board may be swung upwardly to fold the partition, substantially as described.

5. In a folding partition, the combination 55 of a pair of sides of flexible material, a support, the sides being arranged in spaced relation and having their outer edges attached to said support, a strip of flexible material connecting the inner edges of said sides, 60 means for supporting the upper edges of said sides to allow the inner edge thereof to move longitudinally, a board, the board being arranged between the lower edges of said sides, the lower edges of said sides being 65 attached to said board, the board being

hinged at its outer end to a fixed support, a pair of cords, pulleys, the cords being attached to said board and passing over said pulleys, pairs of pulley-wheels, a second pair 70 of pulleys, the free ends of said cords passing under said pairs of pulley-wheels and over said second pair of pulleys and being attached to said board, and means whereby said cords may be pulled upwardly between 75 said pairs of pulley-wheels passing thru the double pulley-block, a pull rope attached to said double pulley block whereby said board may be swung upwardly to fold the partition, and means for holding the pull-rope to hold the partition in locked position, substantially as described.

6. In a folding partition, the combination 80 of a pair of sides of flexible material, a support, the sides being arranged in spaced relation and having their outer edges attached to said support, a strip of flexible material connecting the inner edges of said sides, means for supporting the upper edges 85 of said sides, a board, the board being arranged between the lower edges of said sides, the lower edges of said sides being attached to said board, the board being hinged at its outer end to a fixed support, means for holding said board in its down position, and means for swinging said board upwardly to 90 fold the partition, substantially as described.

7. In a folding partition, the combination 95 of a pair of sides of flexible material, a support, the sides being arranged in spaced relation and having their outer edges attached to said support, a strip of flexible material connecting the inner edges of said sides, means for supporting the upper edges of 100 said sides to allow the inner edge thereof to move longitudinally, a board, the board being arranged between the lower edges of said sides, the lower edges of said sides being attached to said board, the board being hinged at its outer end to a fixed support, means for holding said board at its down position, 105 means for holding said inner corner edges of said sides in vertical alinement, and means for swinging said board upwardly to fold the partition, substantially as described.

8. In a folding partition, the combination 110 of a pair of sides of flexible material, a support, the sides being arranged in spaced relation and having their outer edges attached to said support, a strip of flexible material connecting the inner edges of said sides, means for supporting the upper edges of 115 said sides to allow the inner edge thereof to move longitudinally, a board, the board being arranged between the lower edges of said sides, the lower edges of said sides being attached to said board, the board being hinged at its outer end to a fixed support, means for swinging said board upwardly to fold the partition, and means for forcing 120 the inner side of the partition inwardly 125

toward its original position as said board swings downwardly, substantially as described.

9. In a folding partition, the combination 5 of a pair of sides of flexible material, a support, the sides being arranged in spaced relation and having their outer edges attached to said support, a strip of flexible material connecting the inner edges of said 10 sides, a pair of tracks, roller-wheels in the tracks, the roller-wheels supporting the upper edges of said sides, a board, the board being arranged between the lower edges of said sides, the lower edges of said sides being 15 attached to said board, the board being hinged at its outer end to a fixed support, ropes supported by said roller-wheels adjacent the inner sides of the partition, and the ropes being attached to said board whereby 20 they will be forced into the inner corners of the partition when said board swings downwardly to hold said corners in vertical alinement, substantially as described.

10. In a folding partition, the combination 25 of a pair of sides of flexible material, a support, the sides being arranged in spaced relation and having their outer edges at-

tached to said support, a strip of flexible material connecting the inner edges of said sides, a pair of tracks, roller-wheels in the tracks, the roller-wheels supporting the upper edges of said sides, a board, the board being arranged between the lower edges of said sides, the lower edges of said sides being attached to said board, the board being hinged at its outer end to a fixed support, a shaft, a roller rotatably mounted upon the shaft, ropes supported from said shaft and attached to said board, the ropes being attached to said board whereby they will be 40 forced into the inner corners of the partition when said board swings downwardly to hold said corners in vertical alinement, a belt attached to said board, the belt passing over said roller, and the free end of the belt being attached above said roller whereby when said board is swung downwardly said belt will force said roller inwardly to move the inner side of the partition toward the center, substantially as described.

In testimony whereof I affix my signature.

HERMAN W. MAURER.
